CLAIM

The ornamental design for a cradle for an electronic device, as shown and described.

DESCRIPTION

FIG. 1 is a front left side perspective view of a cradle for an electronic device according to our design;

FIG. 2 is a rear left side perspective view thereof;

FIG. 3 is a front view thereof;

FIG. 4 is a rear view thereof;

FIG. 5 is a right side view thereof with the left side view thereof being a mirror image thereof; and,

FIG. 6 is a top view thereof.

Where included, broken lines showing environment or structure are for illustrative purposes only and form no part of the claimed design.
